(57) CLAIM

I claim the ornamental design for a bottle for containing a liquid, as shown.

DESCRIPTION

FIG. 1 is a front elevational view of a bottle for containing

a liquid showing my new design;

FIG. 2 is a rear elevational view thereof, on a reduced scale;

FIG. 3 is a right side elevational view of FIG. 1;

FIG. 4 is a left side elevational view thereof on a reduced

scale;

FIG. 5 is a top plan view of FIG. 1; and,

FIG. 6 is a bottom plan view of FIG. 1.
